UNITED STATES PATENT OFFICE.

LAWRENCE WAGNER, OF JEFFERSON CITY, MISSOURI.

BOTTLE-WASHER.

SPECIFICATION forming part of Letters Patent No. 243,662, dated June 28, 1881.

Application filed October 19, 1880. (Model.)

To all whom it may concern:

Be it known that I, LAWRENCE WAGNER, of Jefferson City, in the county of Cole and State of Missouri, have invented a new and useful Improvement in Bottle-Washing Machines, of which the following is a specification.

The object of this invention is to provide a more safe, speedy, and simple method of cleaning bottles.

Figure 1 is a side elevation of the device, partly in section, and with parts broken away to exhibit other parts. Fig. 2 is an end elevation of the same.

Similar letters of reference indicate corresponding parts.

In the drawings, A represents the standard supporting the device.

B is a horizontal shaft having one end journaled on said standard A and the other in the hub of the cog-wheel M, and having on one end a crank, B', and on the other end a fly-wheel, B². Fixed rigidly on said shaft B, inside of the uprights of the standard A, are the two wheels or spiders C C, on whose peripheries, at equal distances apart, are formed or secured the journal-boxes c, that serve as bearings for the shafts D, which extend parallel with each other and with the shaft B from one to the other of the wheels or spiders C C.

On each end of each shaft D, within their bearing-points, is rigidly secured a five-armed spider, E, each arm d of which is of sufficient width to support or form an end of a bottle-holding box, G G. Between the arms of the opposite spiders E, extending from one spider E to the opposite one parallel with the shafts D, and surrounding them, are rigidly fixed the rectangular boxes G G, five to each pair of spiders E; hence in the machine herein shown and described are fifteen of these boxes G G, and it is evident that the number may be increased or diminished without departing from my invention. The boxes G G are divided into pockets f f by inclined partitions g g, and in these pockets f f the bottles H H that are to be cleaned are placed in an inclined position, as shown in Fig. 1. Said boxes G G are also

provided with covers h h, that are held down by catches i i, or other suitable devices, as shown, to retain said bottles H H in place during the operation of the machine.

On an end of each shaft D is keyed a cog-wheel, L, all of them in the same plane; and about the shaft B, and in the same plane with the cog-wheels L, is loosely set a cog-wheel, M, fastened to the standard A, and serving as a bearing for an end of the shaft B, into which the cog-wheels L mesh, as shown.

The bottles H H, containing water and shot, or small particles of metal or other hard substance, are closed with suitable stoppers and placed in inclined positions in the pockets f f, as shown, and the covers h h are then fastened down. Said pockets f f are preferably larger than the bottles placed in them, that the bottles may have room to move about a little. Power is then applied to turn the crank B', whereby the boxes G G are revolved in groups around the shaft B by reason of their connection with the spiders C C, and at the same time each group of boxes G G is revolved around its shaft D by reason of the meshing of the cog-wheels L with the cog-wheel M, that is secured on the standard A. Thus it will be seen the bottles H H perform a double revolution at each turn of the crank B', and, by reason of fitting loosely in the pockets f f and being in an inclined position, are also well shaken, so that they are quickly cleaned internally by the water and shot within them.

Having thus fully described my invention, I claim as new and desire to secure by Letters Patent—

In a bottle-washer, the combination of the revolving spiders C C, having the peripheral boxes c c, with the shaft D, carrying pinions L, the shaft B, carrying stationary cog-wheel M, and the revolving spiders E E, having inclined pockets f f and covers h h, as shown and described.

LAWRENCE WAGNER.
